BASE FOR A BLENDER OR THE LIKE

Owner P. Dykes, Lawrence, Kans., assignor to Rival Manufacturing Company, a corporation of Missouri

Filed May 11, 1966, Ser. No. 2,249

Term of patent 14 years

(Cl. D89—1)

Fig. 1.

Fig. 2.

Fig. 3.

Fig. 4.

FIG. 1 is a side elevational view of a base for a blender or the like showing my new design;

FIG. 2 is a front elevational view;

FIG. 3 is a top plan view; and

FIG. 4 is a fragmentary rear elevational view.

The essential features of my new design reside in the portions thereof shown in full lines, while a blender jar is shown in broken line in FIGS. 1-3 for illustrative purposes only.

I claim:

The ornamental design for a base for a blender or the like, as shown and described.
